OUTSOLE ROUGHING MACHINE

Ernest W. Stacey, Beverly, Mass., assignor to
United Shoe Machinery Corporation, Flemington, N. J., a corporation of New Jersey

Application November 24, 1950, Serial No. 197,213

45 Claims. (Cl. 69—1)

1

This invention relates to machines for roughing shoe parts and is herein illustrated as embodied in a machine for roughing the margins of the flesh sides of outsoles preparatory to the cement attachment of said outsoles to shoes.

Machines heretofore used in the preparation of "loose" outsoles for cement attachment to shoes have been subject to various objections, one of said objections being that the roughing tool, in operating upon shank reduced outsoles, tends to destroy the previously formed and desired break line of the outsole. Moreover, difficulty has been experienced in forming on the margin of the flesh side of the outsole a properly roughened band of uniform width and in forming simultaneously therewith at the edge of the outsole a uniformly wide unroughened portion which is sometimes chamfered and which in the finished shoe projects beyond the shoe upper, and accordingly, if not of uniform size and shape, mars the appearance of the shoe.

It is an object of the present invention to provide a roughing machine which will quickly and effectively form on the margin of the flesh side or face of a "loose" shank reduced outsole a uniformly wide roughened band and which will form simultaneously therewith at the edge of said face of the outsole along said band a smooth edge strip or chamfer of uniform size and shape.

With the above object in view, and in accordance with a feature of the present invention, the illustrative machine by the use of which outsoles may be roughened quickly and effectively, comprises a tool rotatable about an axis and having teeth arranged approximately in a frusto conical surface generated about said axis, an arcuate edge gage arranged toward said axis from said frusto conical surface, work feeding means, and mechanism comprising said edge gage for guiding a work piece, for example, a loose outsole, acted upon by said means past the tool, the axis of rotation of the tool lying outside of said outsole and being tilted toward a portion of a face of the outsole being operated upon by said tool.

The present invention consists in the above features and other novel features by the use of which a smooth and evened outer strip may be formed simultaneously with the roughened band and which are hereinafter described with reference to the accompanying drawings showing embodiments of the invention selected for purposes of illustration, the invention being fully described in the following description and claims.

In the drawings,

2

Fig. 1 is a side elevation of the illustrative machine as viewed from the right of the machine;

Fig. 2 is a plan view of the machine;

Fig. 3 is a side elevation of the operating head of the machine as viewed from the left of said machine;

Fig. 4 is a view on line IV—IV of Fig. 2;

Fig. 5 is a view on line V—V of Fig. 3;

Fig. 6 is a plan view, partly broken away, showing portions of the operating head of the machine;

Fig. 7 is a section on line VII—VII of Fig. 6;

Figs. 8 and 9 are views partly on lines VIII—VIII and IX—IX respectively of Fig. 7;

Fig. 10 shows a portion of the drive of the machine as viewed on line X—X of Fig. 1;

Fig. 11 is a section on line XI—XI of Fig. 10;

Fig. 12 is a view showing instrumentalities of the machine in the process of roughing a shank reduced outsole;

Fig. 13 is an enlarged perspective view of an illustrative roughing tool of the machine;

Fig. 14 is a perspective view showing a portion of a roughing tool blades of which are slightly different from blades of the roughing tool shown in Fig. 13;

Fig. 15 is a view on line XV—XV of Fig. 12 showing the roughing tool in the process of operating upon an outsole;

Fig. 16 is a diagrammatic view showing in dash-lines a head of the roughing tool and a frusto conical surface in which tip portions of teeth of the roughing tool travel and also showing the angular relation of said surface and an outsole during the outsole roughing operation;

Fig. 17 is a diagrammatic view showing in plan and on a reduced scale the roughing tool head and the frusto conical surface illustrated in Fig. 16 together with edge gages of the machine and also showing portions of an outsole presented, during two different stages of the outsole roughing operation, to the tool head and the edge gages;

Fig. 18 is a view similar to Fig. 15 but showing a modified tool for simultaneously roughing the margin of the flesh side of an outsole and chamfering the marginal edge of said outsole to the form shown in Fig. 22;

Fig. 19 is a view similar to Fig. 18 illustrating a further modified roughing tool which in addition to roughing the margin of the flesh side of an outsole forms a smooth countersunk strip along the edge of said outsole as shown in Fig. 23;

Fig. 20 illustrates a rough tool similar to that shown in Figs. 13 and 15 but having an inner

tooth of each of its blades removed in order to form on the flesh side of an outsole a roughened band which is spaced from the edge of the outsole by an original portion of the flesh side of the outsole as shown in Fig. 24;

Fig. 21 shows in perspective an outsole which has been operated upon by the machine illustrated in Figs. 1 to 17; and

Figs. 22 to 24 illustrate portions of the outsoles which have been roughened by the machine equipped with the modified tools illustrated in Figs. 18 to 20 respectively.

The illustrative machine will be described with reference to roughing the margins of flesh sides or faces 30 (Figs. 4, 9, 12, 15, 16, 17 and 21) of loose outsoles 32 which have been previously shank reduced to form beveled surfaces 34, and comprises a work feeding and guiding unit 36, an outsole roughing tool 38, a mount 40 for supporting the tool for rotation about an axis 41, and driving mechanism 42 (Figs. 1, 2 and 4) for the tool, said unit and said mount being supported upon a platform 44 secured to the upper end of a fabricated sheet metal column 46 (Fig. 1). Power for operating the machine is supplied by a motor 48 supported upon a pedestal 50 secured to a base portion of the column 46. It is contemplated, if desirable, to provide two motors, one for driving the roughing tool 38 and the other for driving the work feeding and guiding unit 36.

The outsole to be roughened is placed upon a work table 52 by the operator who, after depressing a treadle 54 (Fig. 1) to cause inner and outer concentrically arranged rotatable sleeves or rings 56, 58 (Figs. 3, 4, 6, 7 and 8) on the one hand and a resilient frusto conical feed roll 60 (Figs. 1, 2, 3, 6, 7, 9, and 12) on the other hand to be lowered away from the roughing tool and a toothed feed wheel 62 respectively, manually slides the heel portion of the outsole 32 over the table until its edge engages a cylindrical edge gage 64 and simultaneously therewith slides another portion of the outsole between the feed roll and the toothed feed wheel 62 until its edge engages an edge gage 66. Upon release of the treadle 54 the outsole is gripped between the feed roll 60 and the feed wheel 62 and immediately thereafter is forced against the roughing tool 38 by the sleeves 56, 58, the outsole being moved with cross feed action lengthwise of its margin over the sleeves 56, 58 and past the roughing tool 38 to form on the outsole a roughened band 67 (Fig. 21). When the margin of the outsole has been roughened from a point somewhat rearward of one end of its heel breast line 65 to a point somewhat rearward of the other end of said line, the operator depresses the treadle 54 thereby releasing the outsole from the machine preparatory to manually removing the outsole from the machine and presenting another outsole to be roughened to the machine. It is sometimes desirable to have the roughened band 67 extend around the entire margin of the flesh side 30 of the outsole 32 in which event it is customary to start the roughing operation at the forepart of the outsole and to cause the outsole to make slightly more than a complete revolution in the machine.

The work table 52 is constructed and arranged effectively to support, without assistance by the operator, the outsole 32 as it moves in a closed path lengthwise of its edge past the roughing tool 38. The sleeves or rings 56, 58 which serve as and may be defined as work supports and which may be considered as part of the table, as will

be herein explained, are yieldingly supported independently and are concentrically arranged about an axis 63 of rotation, the upper ends, rims, faces or work supporting and feeding portions of the sleeves being at all times positioned slightly above an upper surface 70 of the table 52 and being adapted effectively to present to the roughing tool 38 the shank reduced outsole 32.

The work feeding and guiding unit 36 comprises a drive sleeve 72 (Figs. 3, 4, 7 and 8) to which a gear 74 is secured by screws 76 (Fig. 7), said sleeve being constrained against vertical displacement in a fixed main frame 78, which is secured to the platform 44, by the gear 74 and by a flange portion 80 of the drive sleeve. The flange portion 80 of the drive sleeve 72 fits in slots 82, 84 formed in the inner and outer sleeves 56, 58 respectively, said drive sleeve having formed in it a bore 86 for receiving slidably a shank 88 of the outer sleeve. The outer sleeve 58 is provided with a bore 90 for receiving a shank 92 of the inner sleeve 56, the lower ends of the shanks 88, 92 of the outer and inner sleeves having formed in them annular grooves 94, 96 for receiving pins 98, 100 (Figs. 3 and 5) carried by inner ends of bifurcated arms 102, 104 pivotally mounted on pins 106, 108 supported in brackets which are secured to the platform 44 and may be considered as part of the frame 78.

The inner ends of the arms 102, 104 are constantly urged upward by springs 114, 116 the upper ends of which are attached to depending lugs secured to the table 52 and the lower ends of which are attached to lugs 109, 111 adjustably mounted in slots 113, 115 (Fig. 5) of said arms. In order to limit the upward extents of movement of the inner and outer sleeves 56, 58 under the action of the springs 114, 116 there are threaded into the outer end portions of the arms 102, 104 screws 118, 120 the lower ends of which are arranged to engage stop faces 122, 124 of lugs which are secured to the platform 44 and constitute part of the frame 78. Outsole engaging rims of the inner and outer sleeves 56, 58 have flattened portions, hereinafter referred to, and when there is no work in the machine the inner sleeve is raised just above the outer sleeve as best shown in Fig. 7. The initial positions of the inner and outer sleeves 56, 58 may be quickly and effectively varied by the use of the screws 118, 120, and the spring applied forces imparting upward movement to the sleeves may be varied by securing the lugs 109, 111 in different operating positions in the slots 113, 115. In order to insure that the sleeves 56, 58 cannot be raised into the path of the roughing tool 38, the arms 102, 104 have secured to them depending bosses 126, 128 which are constructed and arranged to engage the stop faces 122, 124 whenever the screws 118, 120 are removed from the bosses or are so adjusted that their lower ends do not project from said bosses.

The roughing tool 38 comprises a head 130 (Figs. 4, 13 and 14) provided with channels or slots 132 which may be said to face generally lengthwise of the axis 41 of rotation of the tool 38 and in which are secured associated pairs of presser members or feet 134 and blades 136. The bottoms of the channels 132 are inclined to a plane normal to the axis 41 of rotation of the roughing tool 38 at an angle approximately equal to a cone angle of a frusto conical face 135 of the head 130 which conical face may be described as having elements inclined at a slight angle to said plane.

The presser feet 134, except for the slots 138 (Fig. 13) hereinafter referred to, overlie the entire bottoms of associated channels 132, flanges 143 of said presser feet being engaged by associated blades 136 which are illustrated as having teeth 150 at their opposite margins, faces 141 of said flanges being beveled to accommodate back raked edges 145 of the teeth which are forced against said flanges. The presser feet 134 are provided with the slots 138 for receiving pins 140 which are carried by the tool head 130 and project into the corresponding channels 132. The blades 136 have faces provided with frusto conical holes or recesses 142 into which are inserted conical inner ends of screws 144 which are threaded into said head and force the blades against angularly disposed portions of the associated presser feet 134 which may be described as L-shaped.

The channels 132 and accordingly the presser feet 134 and the blades 136 are skewed at angles 148 (Figs. 12, and 17) with relation to associated or corresponding radial planes 149 (Fig. 17) which include the axis of rotation 41 and pass through the outer ends of the presser feet and the blades, thereby insuring that the V-shaped teeth 150, which project beyond work engaging faces 147 of the presser feet and are substantially circumferentially disposed with relation to the axis 41 and which are commonly in alinement with corresponding teeth of the other blades, shall "clear" themselves in the work and assist the presser members in wiping the outsole being roughened inward toward the edge gage 64.

In order further to insure that the teeth 150 of the roughing tool 38 shall "clear" themselves in the work alternate teeth of the blades 136, as shown in Fig. 14, may be eliminated, the construction and arrangement being such that in tools 38 having an even number of blades only the teeth of every other blade are in circumferential alignment.

When the presser feet 134 and the blades 136 have been secured in their operating positions in the tool head 130, leading tips 151 (Fig. 13) of the edges or ridges 145 of the V-shaped teeth 150 of each of the blades lie approximately in a line 152 (Figs. 13, 15 and 16) disposed at approximately 4° to a plane 154 (Figs. 16 and 17) which is at right angles to the axis 41 of rotation of the tool 38 and defines an inner end of a frusto conical surface 153 (Fig. 16) having the axis 41 as a center. The edge or ridge 145 of each of the teeth 150 has a slight back rake as it extends away from the work engaging face 147 of an associated presser member 134. Since the tips 151 of the teeth 150 of each of the blades 136, which tips may be described as apex portions or vertices of the teeth, lie in one of the lines 152, the teeth and their tips may be considered as lying or being disposed approximately in the frusto conical surface 153 elements of which are disposed at a slight angle (approximately 4°) to the plane 154 which intersects the surface 153 and is normal to the axis 41 of rotation of the tool 38. The frusto conical surface 153 in which the tip portions of the teeth 150 lie may also be described as facing away from and at an oblique angle to the axis 41 of rotation of the tool 38 which may be referred to as an end mill roughing tool. The roughing tool 38 may be further described as comprising a plurality of blades 136 which are spaced circumferentially about the axis 41 of rotation of the tool and have rows or series of teeth 150 tips or apex portions 151 of which ex-

tend below or project beyond work engaging surfaces 147 of associated presser feet 134 and lie approximately in the frusto conical surface 153 in which lie the loci of said tip portions of the teeth.

In order that the teeth 150 of the roughing tool 38 shall "dip" into the outsole 32 as they rotat- 5 ingly swing down in the frusto conical surface 153 over and from outside said outsole, the axis 41 of rotation of the tool 38 (Fig. 4) is forwardly tilted approximately 4° from the vertical, said axis being disposed at an acute angle to the face portion of the outsole being roughened and intersecting the axis 68 of rotation of the sleeves 15 56, 58 in the vicinity of the plane 154 (Fig. 16). It will be apparent that when the teeth 150 of each of the blades 136 of the roughing tool 38 are in their lowermost positions the line 152 ex- 20 tends along the tips of the teeth is approxi- 25 mately opposite and is approximately parallel to the portion of the flesh face of the outsole presented by the sleeves 56, 58 to the tool, said teeth because of their entry into the work along a frusto conical path such as above described 30 performing their roughing operation without any substantial amount of bridging action of the outsole lengthwise of its margin. Spaced opposing portions of the faces 166, 168 of the sleeves 56, 58 on the one hand and the frusto conical sur- 35 face 153 on the other hand may be referred to as an outsole receiving notch or gap 159 (Fig. 16) which curves generally about the axes of rotation 41 and 68 of the sleeves and the rough- 40 ing tool and may be defined as arcuate.

The upright drive shaft 131 for the roughing tool 38 is rotatingly mounted in ball bearings 158 (Fig. 4) supported in a bracket or housing 160 which may be quickly and effectively swung or transferred between a full line position shown 45 in Figs. 1 and 4 in which the tool is active and an idle or inactive dash-line position (Fig. 1) in which the blades 136 and/or the presser feet 134 of the tool are changed. The mechanism through which the tool is moved between its active and idle positions will be described in detail later.

The edge gage 64 is illustrated as having a smooth cylindrical face 161, which, if desirable, may be vertically ribbed, and a base portion 162 (Figs. 4 and 7) fitting inside the inner sleeve 66 and secured to said sleeve by a screw 164. When an outsole, the margin of which is of uniform thickness, is being roughened, work engaging faces 166, 168 (Fig. 7) of the sleeves 56, 58 are 50 in substantially horizontal alinement, as shown in full lines (Fig. 15), and when a shank reduced margin is being roughened the face 166 of the inner sleeve is raised with relation to the face 168 of the outer sleeve, as shown in dash-lines 55 in Fig. 15. The upper ends or faces 166, 168 of the sleeves 56, 58, which are independently yieldable lengthwise of their common axis 68 and may be described as a multipart support, may be 60 defined as lying in a plane which is approxi- 65 mately parallel to the line 152 and accordingly parallel to opposing elements of the frusto conical face 153.

The work engaging faces 166, 168 of the yieldable sleeves 56, 58 are curved approximately 70 about the axis 68 of rotation of the sleeves and may be described as arcuate, said axis, as above explained, intersecting the axis 41 of rotation of the tool in the vicinity of the plane 154 (Fig. 16). Since the sleeves 56, 58 are independently 75 yieldable it will be clear that the outsole mar-

ginal face being operated upon will be disposed substantially parallel to opposite elements of the frusto conical surface 153 whether said marginal face is of uniform thickness or is shank beveled. The cylindrical face 161 of the edge gage 64 may be described as arcuate and positioned at one side of the gap or notch 159 and within a projection of the frusto conical face 153 on a plane passing through said face 161 and normal to the axis 41. The cylindrical face 161 of the edge gage 64 may also be described as being closer to the axis 41 of rotation of the tool 38 than is the frusto conical surface 153, as being positioned between the said axis and the outsole supporting portion of the sleeves 56, 58 or the outsole support, or as being positioned between portions of the sleeves and adjacent portions of the axes 41 or 68.

The roughing tool 38 is preferably rotated in a direction opposite to the direction of movement of the outsole past the tool and opposite to the direction of rotation of the sleeves 56, 58, the surface speeds of the faces 166, 168 of the sleeves usually being considerably greater than the speed imparted to the outsole by the feed roll 60 and the feed wheel 62 which may also be referred to as a roll. As above stated the sleeves 56, 58 which constitute part of the table may be referred to as a rotatable portion of said table. The axis of rotation 68 of the edge gage 64 is disposed approximately at right angles to the face 70 of the table 52 and lies in a plane normal to the axis of the feed roll 60 at the work-engaging portion of said feed roll.

Mounted upon a shoulder 170 (Figs. 3, 4 and 7) of the frame 78, and held in adjustment on said shoulder by a binding screw 172 (Figs. 7 and 8) screwed to the frame, is a drive supporting beam 174 which as hereinafter explained carries the edge gage 66 and has rotatably mounted in it mechanism for rotating said gage, the beam being held in different adjusted positions upon the shoulder 170 by a clamp plate 176 (Figs. 3, 4, 6 and 8) forced against said beam by a screw 178 threaded into the frame 78 and passing through an elongated slot 180 (Figs. 3 and 6) in the beam.

The motor 48 has a shaft 182 (Fig. 1) to which is secured a pulley 184 driving through a belt 186 (Figs. 1 and 2) a pulley 188 secured to a shaft 190 rotatable in bearings in the frame 78. Power for operating the work feeding and guiding unit 36 is supplied by the shaft 190 which has secured to it a pulley 192 driving a belt 194 which passes over idler pulleys 196 and drives a pulley 198 secured to the drive shaft 131 of the roughing tool 38. Fixed to the shaft 190 is a worm 202 (Figs. 10 and 11) which meshes with a worm gear 204 fixed to a vertical shaft 206 (Figs. 7, 9, 10 and 11) rotatably mounted in the frame 78.

Operatively connected to the shaft 206 through a coupling 208 is another vertical shaft 210 rotatable in the frame 78 and having secured to it gears 212, 214. The gear 212 drives through an idler gear 218, which is mounted upon a pivot pin 220 secured to the frame 78, a large gear 216 forming part of the drive for the feed roll 60, the gear 214 forming part of the drive for the work supporting sleeves 56, 58. The gear 212 also drives a large gear 222 (Figs. 3, 5, 8 and 9) forming part of the drive for operating the toothed feed wheel 62. Secured to the upper end of the shaft 210 is a gear 224 which meshes with a wide gear 226 secured to the lower end of a vertical shaft 228 journaled in the beam 174.

The edge gage 66 has a bore 230 (Fig. 9) for receiving the upper end of a shaft 232 and is secured to said shaft by a screw 234. The shaft 232 is rotatably mounted in the beam 174 and has secured to its lower end a gear 236 (Figs. 3, 7 and 8) meshing with an idler gear 233 (Figs. 1 and 8) which is secured to a shaft 235 journaled in the beam and which is operatively connected to the gear 226.

10 As above explained, the edge gage 66 is adjustable to a slight extent together with the beam 174 about the axis 68 of rotation of the sleeves 56, 58 in order to expedite the feeding of the outsoles of different sizes and/or shapes past the roughing tool 38. Such adjustment may be readily effected by releasing the clamp screw 178 to release the clamp plate 176 and after swinging the beam 174 to the proper adjusted position about the axis 68 again turning the screw 178 to force the clamp plate against the beam. The maximum angular adjustment of the edge gage 66 about the axis 68 of rotation is only a few degrees.

15 The resilient feed roll is compressible against spring action and is also initially adjustable in directions 238 (Figs. 2, 6, 9 and 12), the toothed feed wheel or roll 62 being fixed against vertical movement by being initially adjustable, as will be herein explained, about a common axis 240 of rotation of the shafts 206, 210 in order to vary the amount of cross feed force applied to the outsole. The toothed feed wheel 62 is formed integral with a shaft 242 (Figs. 1, 2, 6 and 9) which is rotatably mounted in a yoke 244 and has secured to its upper end a bevel gear 246 meshing with a bevel gear 248 secured to an upper vertical shaft 250 journaled in the yoke and coupled to a lower vertical shaft 252 (Figs. 8 and 9) also rotatably mounted in said yoke which comprises upper and lower parts secured together by screws 253 (Figs. 2, 6 and 9). Secured to the lower end of the shaft 252 is the large gear 222 which through mechanism above described is operated by the horizontal drive shaft 190.

20 The feed roll 60 has a hard rubber periphery and a steel core 254 (Fig. 9) pinned to a shaft 256 which is arranged approximately parallel to the upper surface 70 of the table 52 and is mounted for rotation in bushings 258 in a carrier 260 pivotally mounted on a shaft 262 journaled in bushings 264 mounted in the frame 78. The forward end of the shaft 262 has secured to it a bevel gear 266 (Figs. 6, 7, 9 and 12) meshing with a bevel gear 268 secured to the upper end of a shaft 270 which is journaled in the frame 78 and has secured to its lower end the large gear 216. The feed roll 60 is constantly urged bodily clockwise as viewed in Fig. 7 by a spring 272 (Figs. 1, 6, 7, 8 and 9) upper and lower ends of which are attached to a threaded pin 274 secured to the carrier and to a beam 273 (Figs. 1 and 8) attached to an adjustable lever 275 mounted upon the frame 78. Clockwise movement of the carrier 260 upon the shaft 262 (Fig. 7) and accordingly upward movement of the feed roll 60 is limited by a screw 277 which is threaded into the frame 78 and has its upper end normally engaged by the carrier.

25 The feed roll 60 is depressed against the action of the spring 272 preparatory to presenting the outsole to the machine by depressing the treadle 54 and thus swinging a lever 278, operatively connected to the treadle, counterclockwise as viewed in Fig. 7. The lever 278 has secured to its right end (Fig. 7) a stud 280 engaging in a slot 282

formed in a link 284 pivoted upon the pin 274. Upon counterclockwise rotation of the lever 278 the stud 280 is forced against the upper end of the slot 282 causing the link 284 to be moved upward and the carrier 260 to be swung counterclockwise (Fig. 7) about the shaft 262.

During the outsole roughing operation the feed roll 60 is depressed different distances against the action of the spring 272 from its initial raised position in accordance with the thickness of the outsole and the portion of the outsole being operated upon, the link 284 being raised or lowered with relation to the lever 278 by reason of the above described stud and slot connection between these members. The carrier 260 for the feed roll 60 in may be initially adjusted upon the shaft 262 in the direction of the arrows 238 to bring it close to the edge gage 66 by rotating a rod 286 (Figs. 1, 3, 6, 7 and 12) which passes through a bore 288 in one portion of the frame 78 and is threaded into another portion of said frame, the rod fitting in a notch 290 in a flange 292 of the carrier and having secured to it a pair of collars 294 which engage opposite sides of said flange. Housed in the carrier 260 and secured to the shaft 262 is a gear 296 (Figs. 7 and 12) operatively connected through idler gears 298, 300 journaled in the carrier to a gear 302 fixed to the shaft 256 to which the feed roll 60 is secured. With the above construction it will be apparent that the feed roll 60 may be initially adjusted in the direction of the arrows 238 to move said roll as near as possible without interference, to the edge gage 66.

As above explained, in order to vary the cross feed force applied to the outsole during the roughing operation the feed wheel 62 may be initially adjusted about the axis 240 which, as shown in Fig. 7, extends thicknesswise through the portion of the outsole gripped by the roll 60 and the feed wheel 62. Such adjustment is made possible by providing the yoke 244 with a bore 304 (Figs. 7 and 9) in which registers a portion of the bushing for the shaft 210 and a bore in which registers a bushing for the shaft 206. A base portion of the yoke 244 has formed in it an arcuate slot 308 which is centered about the common axis 240 of the shafts 206, 210 and through which passes a setscrew 312 threaded into the frame 78 and having its head overlying a base of the yoke, said setscrew, when tightened to force its head against the yoke, serving to secure said yoke in its initially set position about said axis. The toothed feed wheel 62 may be described as being initially adjusted about the axis 240 which is disposed at approximately right angles to the surface 70 of the table 52 and passes approximately through the axis of rotation of the feed roll 60 and through opposite bite portions of said roll and said wheel which may be referred to as outsole feeding means spaced from and in advance of the roughing tool 38.

The lever 278 is journaled upon a pin 314 (Figs. 5, 7 and 8) secured to the frame 78 and is operatively connected to the upper end of a rod 316 (Figs. 1, 3 and 5) which is constantly urged upward by a spring 318 (Fig. 1). The lower end of the rod 316 is pivotally connected to the treadle 54 which is secured to a pin 320 fulcrumed in the base of the column 46, upward movement of the treadle being limited by the engagement of a screw 322, which is carried by a lug 323 secured to the pin, with said base. The rear end of the lever 278 is operatively connected to the link 284 and the forward portion of said lever overlies a depending lug 324 (Figs. 3 and 5) secured by

5 screws 326 to the bifurcated sleeve operating arm 104. Upon depression of the treadle 54 the lever 278 is rotated counterclockwise as viewed in Figs. 3 and 7 causing the arm 104 to swing counterclockwise about its pivot pin 108 thereby lowering the inner sleeve 56 and then the outer sleeve 58 and depressing, through mechanism above described, the feed roll 60 to enable the operator to present an outsole between the tool 38 and the sleeves 56, 58 on the one hand and the feed roll 60 and the feed wheel 62 on the other hand.

10 The bracket 160 in which the tool 38 is rotatably mounted is supported upon a threaded pivot pin 328 (Figs. 1, 2, 3 and 4) which is secured against rotation in upstanding bifurcated portions of the frame 78 and onto which is threaded a nut portion 330 of a manually actuated cam lever 332 which may also be described 15 as a cam. Formed integral with the bracket 160 is an arm 334 pivotally connected through an expandable connection 336 to one arm of a bell crank lever 338 mounted upon a pin 340 supported by the frame 78. The bracket 160 may 20 be swung upon the pin 328 back to an idle or inactive position after swinging a latch 342, which is mounted upon a pivot pin 344 carried by the frame 78, counterclockwise as viewed in Fig. 4, against the action of a spring 346 and away from a face 348 of the lever 338 and breaking a toggle 350 formed by the lever and the connection 336. Also fulcrumed on the pin 340 is 25 a bell crank lever 352 an upstanding arm of which carries a roll 354 and a horizontal arm 356 of which overlies a rearward projection of the latch 342, the upstanding arm of the lever 352 normally being held against the frame 78 by a spring 358.

30 When the manually actuated cam lever 332 is in its position illustrated in Fig. 4 and the tool 38 carried by the bracket 160 is in its active position said lever through its nut portion 330 draws the bifurcations of the frame 78 against opposite sides of the bracket 160 and binds said bracket rigidly to the frame. When it is desirable to change the tool 38 the operator swings the cam lever 332 counterclockwise (Fig. 4) thus backing the nut portion 330 off the threaded pin 328 and causing a rear edge of said lever to engage the roll 354 and also causing the bell crank lever 352 and accordingly the latch 342 to swing counterclockwise upon their associated pivot pins 340, 344 respectively against the action of the springs 358, 346 with the result that the latch 342 is moved out of contact with the surface 348 of the lever 338. The bracket 160 is then manually 35 swung rearward to its dash-line position shown in Fig. 1 preparatory to working on the tool. After the tool has been reconditioned and has been swung forward to its active position the latch 342 is released to allow it to swing under the action of the spring 346 into engagement with the surface 348 of the bell crank lever 338 thereby preventing the then straightened toggle 350 from being broken. The manually actuated cam lever 332 is then swung clockwise to its 40 position shown in Fig. 4 to bind the bracket 160 rigidly to the frame 78.

45 The roughened band 67 formed at the margin of the flesh side or face of the outsole 32 usually extends to the edge of the outsole, said edge of the outsole in the finished shoe "hugging" the shoe upper to produce what is commonly referred to as "close edge" work.

50 In the manufacture of shoes having cement at-

tached outsoles which project slightly beyond the bottoms of said shoes it is desirable that projecting margins of the outsoles shall be unroughened and clean, that is, free from cement. In the manufacture of outsoles 32A (Figs. 18 and 22) 32B (Figs. 19 and 23) and 32C (Figs. 20 and 24), which are adapted for attachment to shoes of the type just referred to, it is desirable to form roughened bands 67A, 67B and 67C which stop short of the edges of the respective outsoles, the portions of the flesh sides 30A, 30B and 30C of the outsoles adjacent to said edges comprising a chamfered strip 360 such as illustrated in Figs. 18 and 22, a flat countersunk strip 362 such as illustrated in Figs. 19 and 23 or an unroughened strip 364 of the original flesh side 30C of the outsole as illustrated in Figs. 20 and 24.

The outsoles 32A and 32B may be simultaneously roughened and edge reduced by slightly modifying the edge gage 64 and the blades 136 of the roughing tool 38 of the above illustrated machine. The machine modified as illustrated in Fig. 18 comprises an edge gage 64A somewhat lower than the edge gage 64 and a roughing tool 38A having blades 136A each of which has teeth 150A for forming the roughened band 67A and a chamfering tooth 67 for forming the chamfered strip 360.

The machine modified as illustrated in Fig. 19 comprises an edge gage 64B substantially identical with the gage 64A and a roughing tool 38B having blades 136B each of which has teeth 150B for forming the roughened band 67B and a tooth 368 for forming the countersunk strip 362.

In order to form upon the outsole 32C the roughened band 67C which is spaced a substantial distance from the edge of the outsole the innermost tooth of each of the blades 136 of the roughing tool 38 is ground off as illustrated in Fig. 20.

Having described the invention, what I claim as new and desire to secure by Letters Patent of the United States is:

1. In an outsole roughing machine, a roughing tool rotatable about an axis, said tool having teeth the loci of which, when the tool is rotated, lie substantially in a frusto conical surface, a work support which is arranged in opposed relation to the tool, and means comprising an edge gage for guiding an outsole upon said work support past the tool, portions of the edge gage engaged by the outsole being positioned between an adjacent portion of said axis of rotation of the tool and the portion of the support engaged by the outsole.

2. In a roughing machine, a roughing tool rotatable about an axis, said tool having teeth edges of which lie substantially in a frusto conical surface generated about said axis, a support arranged in opposed relation to the tool, and means comprising an edge gage for guiding an outsole on the support past the tool, said axis being positioned a substantial distance outside of the outsole being operated upon and being inclined at an acute angle to a general plane of the portion of the outsole being operated upon.

3. In a roughing machine, a roughing tool rotatable about an axis, said tool having teeth edges of which lie substantially in a frusto conical surface centered at said axis, a support arranged in opposed relation to the tool and yieldable in a rectilinear path inclined at a slight angle to said axis, and means comprising an edge gage for guiding an outsole over the support and past the tool, said axis of rotation of the tool at all times being positioned a substantial distance outside of the outsole being operated upon and being tilted

toward the outsole at an acute angle to a portion of a face of said outsole being operated upon.

4. In an outsole roughing machine, a tool rotatable about an axis, said tool comprising a head carrying roughing teeth which, when the tool is rotated, travel approximately in a frusto conical surface which faces away from said axis at an oblique angle thereto, a yieldable support which is arranged opposite the frusto conical surface and is adapted to force an outsole against said head and said roughing teeth, and means for guiding an outsole upon the support past the tool, said means comprising an edge gage provided with a cylindrical face which is positioned adjacent to the work support and within a projection of said frusto conical surface on a plane passing through said cylindrical face and disposed at right angles to the axis of rotation of the tool.

5. In a roughing machine, a roughing tool rotatable about an axis, said tool comprising, a head carrying roughing teeth which, when the tool is rotated, travel approximately in a frusto conical surface which faces away from said axis at an oblique angle thereto, a work support having a face which is positioned opposite said frusto conical surface and is arranged approximately in parallel relation to opposed elements of said frusto conical surface, and means comprising an edge gage which has a face for guiding an outsole upon the support past the tool, said face of the edge gage being positioned adjacent to said support and to said frusto conical surface and being arranged closer to said axis of rotation of the tool than is said frusto conical surface.

6. In a roughing machine, a tool rotatable about an axis, said tool having teeth apex portions of which, when the tool is rotated, move approximately in a frusto conical surface which faces away from said axis at an oblique angle thereto, a work support positioned opposite said frusto conical surface, and means comprising an edge gage having a work engaging face for guiding an outsole upon said support past the tool, said face of the edge gage being positioned toward said axis from a projection of the frusto conical surface on a plane which is normal to the axis of rotation of the tool and passes through said work engaging face.

7. In a roughing machine, a roughing tool rotatable about an axis, said tool having teeth apex portions of which, when the tool is rotated, move approximately in a frusto conical surface which faces away from said axis at an oblique angle thereto, a support positioned opposite said frusto conical surface, and means comprising an edge gage having a face for guiding an outsole mounted upon said support past the tool, said face of the edge gage being positioned between the axis of rotation of the tool and the portion of the support engaged by the outsole.

8. In a roughing machine, a roughing tool rotatable about an axis, said tool having teeth edges of which, when the tool is rotated, move approximately in a frusto conical surface which faces away from said axis at an oblique angle thereto, a support which is positioned opposite said frusto conical surface and forms an outsole receiving notch therewith, said support being rotatable about an axis disposed at a slight angle to the axis of rotation of the tool and being yieldable lengthwise of said axis, and means comprising an edge gage having a face for guiding an outsole upon said support past the tool, said face of the edge gage lying toward said axis from a projection of the frusto conical surface on a plane

normal to the axis of rotation of the tool and passing through said face of the edge gage.

9. In a roughing machine, a roughing tool rotatable about an axis, said tool having teeth which, when the tool is rotated, move approximately in a frusto conical surface which faces away from said axis at an oblique angle thereto, a support which is arranged opposite said frusto conical surface and is approximately parallel to elements of opposed portions of said frusto conical surface, and means comprising an edge gage having a face for guiding an outsole mounted upon said support past the tool, said face of the edge gage being positioned adjacent to and radially toward said axis from the frusto-conical surface and from the portion of the support engaged by the outsole.

10. In an outsole roughing machine, a roughing tool rotatable about an axis, concentric work supporting sleeves which are rotatable about an axis inclined at a slight angle to the axis of rotation of the tool and are independently yieldable lengthwise of said axis, work feeding means, and means for guiding work acted on by said feeding means over the sleeves and past the tool, said work guiding means comprising a cylindrical edge gage which is concentric with said sleeves and is rotatable with said sleeves.

11. In an outsole roughing machine, a roughing tool rotatable about an axis, work supporting members which are rotatable about an axis inclined to and substantially intersecting the axis of rotation of the tool and which are independently yieldable lengthwise of their axis, work feeding means, and means for guiding work acted upon by said feeding means over said members and past the tool, said guiding means comprising a cylindrical edge gage which is concentric with said work supporting members and is rotatable together with said members.

12. In an outsole roughing machine, a tool rotatable about an axis and having teeth apex portions of which are arranged substantially in a conical surface elements of which are inclined to said axis, a multipart support for an outsole, gages which are engaged by the edge of the outsole upon the support, and means for feeding the outsole guided by said gages over the support and past the tool to roughen a face of said outsole, the axis of rotation of the tool lying outside the outsole being roughened and being tilted toward the outsole at an acute angle to the general plane of said face of the outsole being roughened.

13. In an outsole roughing machine, a work support comprising a plurality of arcuate members which are curved about an axis and are independently yieldable generally lengthwise of said axis, work feeding means, work guiding means comprising an edge gage having an arcuate work engaging face which is coaxial with said axis and is coextensive with said members, and a roughing tool rotatable about an axis and having teeth arranged generally in a frusto conical surface which faces away from said axis at an oblique angle thereto and which is arranged opposite said work support and is positioned adjacent to said work engaging face of the edge gage.

14. In an outsole roughing machine, a table having a face for supporting an outsole, a driven feed roll rotatable about an axis disposed generally parallel to said face of the table, an associated driven feed wheel which is positioned adjacent to said roll and is rotatable about an axis disposed at a substantial angle to the first-

named axis, a roughing tool rotatable about an axis inclined at an acute angle to said face of the table, an edge gage positioned adjacent to and at one end of the feed roll, means for rotating the edge gage, a second edge gage which is positioned beneath said tool and is rotatable about an axis which is arranged at substantially right angles to the face of the table and substantially in a plane disposed at right angles to the axis of rotation of the feed roll at its work engaging portion, means for driving the second-named edge gage, and a rotatable table portion which projects slightly above the table and is positioned beneath the tool and adjacent to the second-named edge gage.

15. In an outsole roughing machine, a table having a face for supporting an outsole, a driven feed roll rotatable about an axis disposed generally parallel to said face of the table, a driven feed wheel which is positioned adjacent to said roll and is rotatable about an axis disposed at a substantial angle to the first-named axis, a roughing tool rotatable about an axis disposed at an acute angle to the face of the table, an edge gage positioned adjacent to one end of the feed roll, means for rotating the edge gage, a second edge gage positioned beneath said tool and rotatable about an axis which is approximately normal to said face of the table and lies substantially in a plane disposed at right angles to the axis of the feed roll at its fork engaging portion, means for driving the second-named edge gage, and a pair of driven independently yieldable sleeves which are rotatable about an axis disposed at right angles to the face of the table and have their upper ends arranged slightly above the table and positioned opposite the roughing tool and adjacent the second-named edge gage.

16. In a machine for roughing shoe parts, a roughing tool, a table adapted to support work against the action of said tool, edge gages, a resilient feed roll and a cooperating toothed feed wheel which are rotatable about axes inclined to each other and are constructed and arranged to feed work guided by said gages over the table and past the tool, and means for initially setting the toothed feed wheel into different active positions about an axis which is disposed approximately at right angles to the table and which passes approximately through the axis of the feed roll and through opposite bite portions of the feed roll and the feed wheel.

17. In a roughing machine, a plurality of concentric work supporting rings which rotate in one direction about an axis and are independently yieldable lengthwise of said axis, a roughing tool which rotates in a direction opposite to the direction of rotation of the rings and which comprises a plurality of teeth spaced from and arranged in opposed relation to said rings, and means for guiding a work piece over the rings and past the tool to prepare a surface of said work piece for the reception of adhesive.

18. In a roughing machine, an end mill roughing tool rotatable about an axis and having rows of teeth which are spaced circumferentially of said axis, a work support comprising a plurality of concentric rings rotatable about and yieldable lengthwise of an axis which substantially intersects and is inclined at a slight angle to the axis of rotation of the tool, and means for guiding a work piece over the rings and past the tool to prepare a surface of said work piece for the reception of adhesive.

19. In a roughing machine, an end mill roughing tool rotatable about an axis and having teeth which are arranged substantially in a frusto conical surface, a work support comprising a plurality of concentric rings rotatable about and yieldable lengthwise of an axis which substantially intersects and is inclined at a slight angle to the axis of rotation of the tool, means for rotating the tool on the one hand and the rings on the other hand in opposite directions, and means for guiding work over the rings and past the tool to prepare a surface of the work for the reception of adhesive.

20. In an outsole roughing machine, an arcuate work support, a rotatable roughing tool positioned opposite said support and forming an arcuate notch therewith, an arcuate edge gage which is arranged approximately concentrically with relation to said tool, feed rolls for moving an outsole over the support and past the tool, an edge gage positioned at one end of the rolls, means for moving the last-named edge gage into different adjusted positions, and means for moving one of the feed rolls into different adjusted positions adjacent to the last-named edge gage.

21. In an outsole roughing machine, an arcuate work support, a rotatable roughing tool positioned opposite said support and forming an arcuate notch therewith, an arcuate edge gage which is arranged approximately concentrically with relation to said tool, feed rolls for moving an outsole over the support and past the tool, an edge gage positioned at one end of the rolls, means for moving the last-named edge gage into different adjusted positions, means for moving one of the feed rolls into different adjusted positions adjacent to the last-named feed roll, and means for angularly adjusting the other feed roll with relation to said one feed roll about an axis extending thicknesswise through the portion of the outsole gripped by said rolls.

22. In a roughing machine, a tool rotatable about an axis and having teeth arranged approximately in a frusto conical surface generated about said axis, an arcuate edge gage arranged toward said axis from said frusto conical surface, work feeding means, and mechanism comprising said edge gage for guiding a loose outsole acted upon by said means past the tool, the axis of rotation of the tool lying outside of said outsole and being tilted toward a face portion of the outsole being operated upon by said tool.

23. In a roughing machine, a tool rotatable about an axis and having teeth arranged approximately in a frusto conical surface centered at said axis, an arcuate support which is spaced from and is arranged opposite said surface to form an arcuate notch and which is centered approximately at said axis and is yieldable generally lengthwise of said axis, an arcuate edge gage which is centered approximately at said axis and is arranged at one end of said notch and toward said axis from said frusto conical surface and the support, work feeding means, and mechanism comprising said edge gage for guiding a loose outsole acted upon by said feeding means past the tool, the axis of rotation of the tool lying outside of said outsole and being tilted toward the portion of a face of the outsole which is in said gap and is presented to the tool.

24. In an outsole roughing machine, a tool rotatable about an axis and having teeth arranged approximately in a frusto conical surface centered at said axis, a sleeve which is spaced from and is arranged opposite said frusto conical sur-

face and which is rotatable about an axis and is yieldable lengthwise of its axis, an edge gage having a work engaging surface which is centered approximately at said second-named axis and is arranged between said second-named axis and the sleeve, rolls for feeding a loose outsole lengthwise of its edge between the sleeve and the tool, means for rotating the tool in a direction opposite to the direction of movement of the outsole, mechanism comprising said edge gage for guiding a loose outsole acted upon by said rolls past the tool, and means for rotating the sleeve in a direction opposite to the direction of rotation of the tool at a surface speed substantially greater than the surface speed imparted to the outsole by said rolls.

25. In an outsole roughing machine, a tool rotatable about an axis and having teeth arranged approximately in a frusto conical surface centered at said axis, a support which is spaced from and is arranged opposite said frusto conical surface and which is rotatable about an axis, an edge gage having a work engaging surface which is centered approximately at said second-named axis and is arranged between said second-named axis and the support, means spaced from and in advance of the tool for feeding a loose outsole lengthwise of its edge between the support and the tool, means for rotating the tool in a direction opposite to the direction of movement of the outsole, mechanism comprising said edge gage for guiding the loose outsole acted upon by said feeding means past the tool, and means for rotating the support in a direction opposite to the direction of rotation of the tool at a surface speed greater than the surface speed imparted to the outsole by said feeding means.

26. In an outsole roughing machine, a tool rotatable about an axis and having teeth arranged approximately in a frusto conical surface centered at said axis, a yieldable support which is spaced from and is arranged opposite said frusto conical surface and which is rotatable about an axis, an edge gage having a work engaging surface which is centered approximately at said second-named axis and is arranged between said support and said second-named axis, rolls for feeding a loose outsole lengthwise of its edge between the support and the tool, mechanism comprising said edge gage for guiding the loose outsole acted upon by said rolls past the tool, and means for moving the portion of the support engaged by the outsole in the same general direction as the outsole and at a greater surface speed than that imparted to the outsole by said rolls.

27. In a roughing machine, a roughing tool rotatable about an axis and comprising a plurality of blades which are spaced circumferentially of said axis and each of which has roughing teeth and an edge trimming tooth tips of which are arranged approximately in a frusto conical surface, said edge trimming teeth of the blades being arranged at an apex portion of said frusto conical surface, a yieldable work support having a work engaging face which is arranged generally in a plane and which is positioned opposite and is spaced from said frusto conical surface to form a notch, and means for guiding and feeding a loose outsole through said notch and past the tool to form a roughened band of uniform width extending along the margin of one side of the outsole and simultaneously therewith to trim an adjacent edge of the outsole to a predetermined shape.

28. In a roughing machine, a roughing tool rotatable about an axis and having roughing teeth and edge trimming teeth tip portions of which are arranged approximately in a frusto conical surface centered at said axis, a yieldable work support having a work engaging face which is arranged generally in a plane and which is positioned opposite and is spaced from said frusto conical surface to form a notch, means for guiding and feeding a loose outsole through said notch and past the tool to form a roughened band of uniform width extending along the margin of one side of the outsole and simultaneously therewith to trim an adjacent edge of the outsole to a predetermined shape, said axis of rotation of the tool lying outside the outsole being operated upon and being tilted toward said notch at a slight angle to the general plane of the work engaging face of the work support.

29. In an outsole roughing machine, a yieldable support, means for guiding an outsole over said support, and a roughing tool which is rotatable about an axis lying outside the outsole guided over said support and which is tilted toward the outsole at a predetermined number of degrees to a general plane of a face portion of said outsole being operated upon, said means comprising an edge gage which is approximately concentric with relation to said axis, said tool having teeth which are arranged approximately in a frusto conical surface elements of which are inclined at approximately said predetermined number of degrees to said axis.

30. In an outsole roughing machine, a roughing tool comprising a head rotatable about an axis and having a frusto conical face which is inclined to said axis and has formed in it a plurality of slots spaced circumferentially of said axis, a plurality of blades which are positioned in the respective slots and are secured to said head, each of said blades having teeth which extend beyond said frusto conical face of the head and are arranged substantially in a conical surface centered approximately at said axis, a yieldable support, and means for feeding and guiding an outsole over the support and past the roughing tool, said means comprising an edge gage having an outsole engaging face which is positioned between said blades and the axis of rotation of the tool.

31. In an outsole roughing machine, a roughing tool comprising a head rotatable about an axis and having a frusto conical face elements of which are inclined to said axis, said face having formed in it slots spaced circumferentially of said axis, a plurality of blades positioned in said slots and secured to said head, each of said blades having teeth tips of which are arranged substantially in a conical surface centered at said axis and projecting beyond the frusto conical surface of the head, a rotatable yieldable support, and means for feeding and guiding the outsole over the support and past the roughing tool, said means comprising an edge gage having an arcuate outsole engaging surface which is positioned between the blades and the axis of rotation of the tool.

32. In an outsole roughing machine, a yieldable support for an outsole, a roughing tool rotatable about an axis, and means for guiding said outsole over said support and past the roughing tool, said axis being positioned outside of the outsole upon the support and guided past the tool and being inclined at a predetermined number of degrees to a general plane of a portion of said

outsole being operated upon, said outsole guiding means comprising an edge gage which is approximately concentric with relation to the axis of rotation of the tool, said tool comprising a plurality of blades which are spaced circumferentially of said axis and each of which has teeth having tips arranged approximately in a frusto conical surface elements of which are disposed at approximately said number of degrees to said axis and which faces away from said axis at an oblique angle thereto, cutting edges of the teeth of each of said blades extending substantially circumferentially of said frusto conical surface and having back rake and each of the blades being skewed with relation to a radial plane including said axis and passing through the blade.

33. In an outsole roughing machine, means for yieldingly supporting an outsole, a roughing tool positioned opposite said means, and mechanism comprising an edge gage for guiding said outsole past said means and said tool to roughen a flesh side of said outsole, said tool being rotatable about an axis which is positioned outside of the outsole being roughened and is tilted toward the outsole at an acute angle to a general plane of said flesh side of the outsole upon said means and guided by said mechanism, said tool having a plurality of circumferentially spaced series of teeth apex portions of which lie approximately in a frusto conical surface elements of which are disposed at a slight angle to a plane normal to said axis.

34. In a roughing machine, a ring support rotatable about an axis, and a roughing tool which is rotatable about an axis inclined at a slight angle to the axis of rotation of the support, said tool being arranged opposite said support and comprising a plurality of blades each of which is skewed with relation to a plane extending through said blade and including said axis and each of which has teeth extending generally circumferentially about said axis.

35. In a roughing machine, a support for a work piece, a roughing tool rotatable about an axis, and means for feeding and guiding the work piece mounted upon the support past the tool, said tool having circumferentially spaced blades each of which is skewed with relation to a plane extending through the outer end of the blade and including said axis, each of said blades having teeth tips of which are arranged substantially in a frusto conical surface which faces away from said axis at an oblique angle thereto, said axis of rotation of the tool lying outside and being tilted toward a portion of the work piece being operated upon by the tool.

36. In a roughing machine, a support for a shoe part, said support being rotatable about an axis, a tool rotatable about an axis inclined at a slight angle to the axis of rotation of the support, and means for feeding and guiding the shoe part mounted upon the support past the tool, said tool comprising circumferentially spaced blades each of which is skewed with relation to a plane extending through the outer end of the blade and including the axis of rotation of the tool, each of said blades having teeth tips of which are arranged in a frusto conical surface which faces away from said axis at an oblique angle thereto.

37. In an outsole roughing machine, a plurality of concentric rings for supporting an outsole, a tool rotatable about an axis, and means for feeding and guiding the outsole supported upon said rings past the tool, said tool comprising a plurality of circumferentially spaced blades each of

which is skewed with relation to a corresponding radial plane, each of said blades having teeth tips of which are arranged in a frusto conical surface which faces away from said axis at an oblique angle thereto, said rings being rotatable about an axis which is inclined at a slight angle to and approximately intersects the axis of rotation of the tool and being yieldable lengthwise of its axis of rotation.

38. In an outsole roughing machine, a roughing tool which is rotatable about an axis and comprises a head having circumferentially spaced slots facing generally lengthwise of said axis, L-shaped members which are constructed and arranged to fit in said slots and having presser surfaces projecting axially beyond said slots, means for retaining said members against displacement lengthwise of the slots, roughing blades each of which fits between a face of the head and a face of an associated member, and means carried by and movable in the head for forcing the blades against angularly disposed surfaces of said L-shaped members to secure said members and said blades against movement in the slots.

39. In an outsole roughing machine, a roughing tool which is rotatable about an axis and comprises a head having circumferentially spaced slots each of which faces generally lengthwise of said axis and has a detent portion formed in it, L-shaped members which are constructed and arranged to fit in said slots and have presser surfaces projecting axially beyond said slots and which have detent portions cooperating with said detent portions of the head to restrain said members against movement lengthwise of the slots, blades which have conical recesses and which fit between faces of the head and faces of said members, and means threaded into the head and having conical ends adapted to be forced into the conical recesses of the blades to force said blades against angularly disposed faces of the L-shaped members to clamp said members and the blades securely in the slots.

40. In an outsole roughing machine, a roughing tool, a frame, a threaded pin mounted in the frame, a bracket in which the tool is rotatably mounted, means for feeding and guiding an outsole past the tool, said bracket being mounted for pivotal movement upon the pin to effect transfer of the tool between an active position adjacent to said means and an idle position remote from said means, means for locating the bracket in a predetermined position and accordingly locating the tool in its active position, a latch associated with said second-named means for securing the bracket against movement from its active position, and manually actuated mechanism movable in one direction to trip the latch and movable in an opposite direction to force the frame in binding relation with the bracket.

41. In an outsole roughing machine, a roughing tool, a frame, a threaded pin mounted upon the frame, a bracket in which the tool is rotatably mounted, means for feeding and guiding an outsole past the tool, said bracket being mounted for pivotal movement upon the pin to effect transfer of the tool between an active position adjacent to said means and an idle position remote from said means, a latch for insuring against movement of the tool away from its active position, and a cam which is threaded onto the pin, said cam being movable in one direction upon the pin to trip the latch to enable the bracket to be swung to its idle position and being

movable in an opposite direction to cause the frame to be rigidly clamped against the bracket to insure against any movement of the frame.

42. In an outsole roughing machine, a roughing tool comprising a head rotatable about an axis, slots which are formed in said head and are spaced circumferentially about said axis, a plurality of presser members and blades which are interchangeably positioned and secured side by side in predetermined positions in said slots, said presser members having work engaging faces which are arranged approximately in a frusto conical surface centered at said axis and said blades having teeth tip portions of which project beyond the work engaging faces of associated presser members and lie approximately in a frusto conical surface centered at said axis, means for securing the presser members in said predetermined positions in the slots, a yieldable support, and means for feeding and guiding the outsole over the support and past the roughing tool.

43. In an outsole roughing machine, a roughing tool comprising a head rotatable about an axis, slots which are formed in said head and are spaced circumferentially about said axis, a plurality of presser members and blades which are interchangeably positioned and secured side by side in said slots, said presser members having work engaging faces which are arranged approximately in a frusto conical surface centered at said axis and said blades having teeth tip portions of which extend below the work engaging faces of associated presser members and lie approximately in a frusto conical face centered at said axis, means for securing the presser members in active positions in the slots, a yieldable support, and means for feeding and guiding the outsole over the support and past the roughing tool, the work engaging faces of the presser members and tip portions of the teeth of the blades being skewed with relation to planes which include said axis and pass respectively through the outer ends of said members and the blades.

44. In an outsole roughing machine, a roughing tool comprising a head rotatable about an axis, slots which are formed in said head and are spaced circumferentially about said axis, a plurality of presser members and blades which are interchangeably positioned and secured side by side in said slots, said presser members having work engaging faces which are arranged in a frusto conical surface centered at said axis and said blades having V-shaped teeth tip portions of ridges of which extend below the work engaging faces of associated presser members and lie approximately in a frusto conical surface centered at said axis, means for securing the presser members in active positions in the slots, a yieldable support, and means for feeding and guiding an outsole over the support and past the roughing tool, said ridges of the teeth extending approximately circumferentially about said axis and having a back rake as they extend away from work engaging faces of their associated presser members.

45. In an outsole roughing machine, a roughing tool comprising a head rotatable about an axis, slots which are formed in said head and are spaced circumferentially about said axis, a plurality of presser members and blades which are interchangeably positioned and secured side by side in said slots, said presser members having work engaging faces which are arranged in a frusto conical surface centered at said axis and

21

said blades having V-shaped teeth tip portions of ridges of which extend below the work engaging faces of associated presser members and lie approximately in a frusto conical face centered about said axis, means for securing the 5 presser members in active positions in the slots, a yieldable support, and means for feeding and guiding the outsole over the support and past the roughing tool, the work engaging faces of the presser members and the tip portions of the 10 ridges of the blades being skewed inward and

22

rearward with relation to planes including said axis and passing respectively through the outer ends of the members and the blades, the ridges of the teeth being disposed circumferentially about said axis and having back rake as they extend away from the work engaging faces of associated presser members.
